CLAIM

The ornamental design for a bottle, as shown and described.

DESCRIPTION

FIG. 1 is a top, right, front perspective view showing our new design for a bottle;

FIG. 2 is a front elevational view thereof, the rear elevational view, the left side elevational view, and the right side elevational view being identical;

FIG. 3 is a top plan view thereof; and,

FIG. 4 is a bottom plan view thereof.

The dash-dash broken lines are for the purpose of illustrating unclaimed subject matter only and form no part of the claimed design. The dash-dot broken lines represent the boundary between claimed and unclaimed areas and form no part of the claimed design.
